(57) **CLAIM**

The ornamental design for a portion of light fixture, as shown and described.

DESCRIPTION

FIG. 1 is a perspective view from below of a portion of light fixture in accordance with my design;

FIG. 2 is a top plan view of the portion of light fixture in accordance with my design;

FIG. 3 is a side elevation view of the portion of light fixture in accordance with my design;

FIG. 4 is an enlarged side elevation view of the portion of light fixture in accordance with my design, all sides being identical except for the positioning of the hooks; and,

FIG. 5 is an enlarged bottom plan view of the portion of light fixture in accordance with my design.

The broken lines showing environment structure are for illustrative purposes only and form no part of the claimed invention.
